United States Patent Office

Des. 229,713

Patented Dec. 25, 1973

229,713

LUMINAIRE

Yearl S. Wince, South Newark, Ohio, and Mitchell Bobrick, Los Angeles, Calif., assignors to Holophane Company, Inc., New York, N.Y.

Continuation-in-part of abandoned design application Ser. No. 19,358, Oct. 1, 1969. This application June 22, 1970, Ser. No. 24,258

Term of patent 14 years

Int. Cl. D26—03

U.S. Cl. D48—31

Fig. 5.

Fig. 6.

Fig. 7.

Fig. 8.

Fig. 9.

Fig. 10.

FIG. 1 is a perspective view of a luminaire showing our new design;

FIG. 2 is a top plan view thereof;

FIG. 3 is a front elevational view thereof;

FIG. 4 is a bottom plan view thereof;

FIG. 5 is a front elevational view of a second embodiment of our new design;

FIG. 6 is a front elevational view of a third embodiment of our new design;

FIG. 7 is a front elevational view of a fourth embodiment of our new design;

FIGS. 8, 9 and 10 are fragmentary views of further embodiments of our new design, all three being identical to FIG. 7 in appearance except for the top cover which is rounded in FIG. 8 and has a photocell unit attached thereto in FIGS. 9 and 10;

FIGS. 11, 12 and 13 are fragmentary views of further embodiments of our new design, all three being identical to FIG. 1 in appearance except for the top cover which is rounded in FIG. 11 and has a photocell unit attached thereto in FIGS. 12 and 13;

FIGS. 14, 15 and 16 are fragmentary views of further embodiments of our new design, all three being identical to FIG. 5 in appearance except for the top cover which is rounded in FIG. 14 and has a photocell unit attached thereto in FIGS. 15 and 16; and

FIGS. 17, 18 and 19 are fragmentary views of further embodiments of our new design, all three being identical

to FIG. 6 in appearance except for the top cover which is rounded in FIG. 17 and has a photocell unit attached thereto in FIGS. 18 and 19.

This is a continuation-in-part of design application 19,358 filed Oct. 1, 1969 and now abandoned.

We claim:

The ornamental design for a luminaire, substantially as shown and described.
